UNITED STATES PATENT OFFICE.

WALTER P. MURPHY, OF CHICAGO, ILLINOIS.

RELEASE-RIGGING.

1,095,222.

Specification of Letters Patent.

Patented May 5, 1914.

Application filed December 27, 1913. Serial No. 809,030.

To all whom it may concern:

Be it known that I, WALTER P. MURPHY, a citizen of the United States, residing at Chicago, county of Cook, and State of Illinois, have invented certain new and useful Improvements in Release-Rigging, of which the following is a specification.

The object of my invention is to provide a release rigging for car couplers, comprising a rock shaft which is flexibly connected at its inner end with the locking pin and is provided with a lever intermediate its ends extending upwardly and rearwardly therefrom, from which is bodily suspended an operating handle, whereby the shaft may be rotated and the locking pin operated when the handle is pushed bodily downward or is moved in an arc; and with this and other objects in view, my invention consists of the parts and combination of parts as will be hereinafter pointed out.

In the drawing: Figure 1 is an end elevation of a car (broken away) equipped with my improved release rigging. Fig. 2 is a top plan view of the same. Fig. 3 is an enlarged detail vertical sectional view on the line 3—3 Fig. 1 looking in the direction of the arrows. Fig. 4 is an end elevation of a car (broken away) with a release rigging, secured thereto showing another embodiment of my invention. Fig. 5 is a vertical sectional view on the line 5—5 Fig. 4 looking in the direction of the arrow. Fig. 6 is a detail perspective view of still another embodiment of my invention. Fig. 7 a detail perspective view of still another embodiment of my invention.

The reference numeral 8 designates a car and 9 the coupler. The release rigging rock shaft 10 is revolvably mounted in brackets 11 secured to the car; the inner end of the rock shaft terminating in a forwardly extending crank 12 which is flexibly connected with the locking pin of the coupler. The rock shaft is provided intermediate its ends with a lever 12^a which, when the shaft is in operative position on the car, extends rearwardly and upwardly at an acute angle from the rock shaft toward the car, and is provided with a bolt opening near its upper end.

13 is a handle terminating at its upper end in a yoke 14, the arms of which straddle the lever 12 to which they are pivotally secured by means of a bolt 15, whereby the handle is bodily suspended from the lever 12

intermediate the ends of the rock shaft. The handle 13 terminates at its lower end in an outwardly extending crank 16 which lies, normally, in a plane beneath the plane of the underface of the car or end sill of the car where it is within easy reach of the brakeman, whether he is standing on the road bed or on the usual side step of the car.

Referring to Figs. 4 and 5 the reference numeral 17 designates the rock shaft of the release rigging suitably mounted on the car by means of the brackets 18. This lever is provided, intermediate its ends, with a lever 19, of the box type, extending upwardly therefrom, toward the car, at an acute angle. 19^a is an operating handle, the upper end of which is rebent to form an eye 20 which is disposed around the upper end of the lever 19 as more clearly shown in Fig. 5, whereby the handle is suspended bodily from said lever between the rock shaft and the car. The lower end of the handle 19^a terminates in an outwardly extending crank 21, which, normally, lies in a plane below the plane of the underface of the car in which position it may be easily operated by the brakeman from the road bed or from the car.

In Fig. 6 I have shown another embodiment of my invention in which the rock shaft 22 is broken away. The rock shaft 22 is provided, intermediate its ends, with a lever 23 which extends therefrom rearwardly and upwardly toward the car body. 90 This lever 23 is formed by closed return bend of the shaft, the portions 24 abutting and constituting a fulcrum when the operating handle is operated as a lever of the first order as will be hereinafter explained. The 95 operating handle 25 terminates at its upper end in a return bend to form an eye 26 which engages the lever 23, as shown, the lower end of the handle terminating in an outwardly extending crank 21 which is normally in a plane beneath the plane of the underface of the car or end sill as heretofore explained in connection with the other embodiments of my invention.

In Fig. 7 the rock shaft 28 is shown 105 broken away. The rock shaft 28 is provided, intermediate its ends, with a lever 29 which extends therefrom rearwardly and upwardly toward the car. 30 is an operating handle which is rebent at its upper end to form an 110 enlarged eye or ring 31 which is at right angles to the crank 32 at the lower end of

the handle, the sides of the ring contacting with the shaft 28 when the handle is used as a lever of the first order, the shaft acting as fulcrum. The handle 30, as in the other embodiments, is suspended bodily from the lever 29 between the shaft and the car.

From the above description it will be seen that a brakeman standing on the usual side step of a car may operate the locking pin 10 of the coupler by pressing downward with his foot on the crank of the operating handle thus pushing the handle downward bodily in a vertical plane thus, through the lever on the rock shaft, (which operates as 15 a crank) rotate the rock shaft and operate the locking pin of the coupler.

When standing on the road bed beside the car, the brakeman may pull on the crank of the operating handle and swing said handle in an arc, whereupon the handle, near its upper end, is brought into contact with the rock shaft and said shaft serves as a fulcrum for said handle, whereby the handle becomes a lever of the first order, and 25 rotates the shaft thereby operating the locking pin of the coupler. Thus it will be seen that the rock shaft may be rotated either by

a vertical plane movement or an arcuate movement of the operating handle.

What I claim is:

1. In a release rigging for car couplers, a rock shaft connected with the coupler pin at its inner end, a crank on said shaft intermediate its ends and extending upwardly and rearwardly therefrom, an operating handle suspended bodily from said crank, whereby the shaft is rotated when the handle is pushed bodily downward, and said handle engaging said shaft intermediate its ends whereby said shaft is rotated when the handle is moved in an arc. 40

2. In a release rigging for car couplers, a rock shaft to operate the locking pin of the coupler, and having an offset, and an operating handle suspended bodily from said offset and having a further operative point of connection with said shaft. 45

In testimony whereof I affix my signature in presence of two witnesses.

WALTER P. MURPHY.

Witnesses:

HARRY W. STANNARD,
P. F. McSHANE.
